G. COSMOS.

TOILET POWDER RECEPTACLE AND BRUSH.

APPLICATION FILED NOV. 26, 1920.

1,380,884.

Patented June 7, 1921.

INVENTOR

GEORGE COSMOS,

By Ralph Taubish ATTORNEY.

UNITED STATES PATENT OFFICE.

GEORGE COSMOS, OF ST. LOUIS, MISSOURI.

TOILET-POWDER RECEPTACLE AND BRUSH.

1,380,884.

Specification of Letters Patent. Patented June 7, 1921.

Application filed November 26, 1920. Serial No. 426,590.

To all whom it may concern:

Be it known that I, GEORGE COSMOS, a citizen of the United States, residing at the city of St. Louis, State of Missouri, (whose post-office address is 1532 Market street, St. Louis, Missouri,) have invented a certain new and useful Combined Toilet-Powder Receptacle and Brush, of which the following is a specification, reference being had to the accompanying drawing, forming a part thereof.

This invention relates generally to toilet articles and, more particularly, to a certain new and useful combined toilet-powder receptacle and brush especially adapted for barbers' use.

The principal object of my present invention is to provide a toilet-powder receptacle and brush so constructed and combined in one article that the toilet-powder contents of the receptacle may selectively be either sprinkled directly from the receptacle, as with the ordinary or common talcum-powder can or other toilet-powder receptacle now in general use, or applied by the barber or other user through and by the brush, and the brush selectively employed, as may be desired, either as a duster alone or both as a duster and powder applicator, as, for instance, after hair-cuts and the like.

A further object of my present invention is to provide a toilet-brush having a handle adapted not only for the convenient manipulation of the brush, but also for employment as a magazine or receptacle for supplying toilet-powder to the brush while in use.

An additional object of my present invention is to provide a brush of the type described with simple, easily actuated means, whereby the supply of powder from the magazine to the brush may be conveniently controlled at will.

With the above and other objects in view, my present invention resides in the novel features of form, construction, arrangement, and combination of parts hereinafter described and afterward pointed out in the claims.

In the accompanying drawings,

Figure 1 is a vertical sectional elevation of a combined toilet-brush and toilet-powder receptacle constructed in accordance with and embodying my invention;

Fig. 2 is a detail sectional elevation of

the brush taken approximately on the line 2-2, Fig. 1, showing a means for controlling the discharge of powder directly from the handle of the article; and

Fig. 3 is a similar view, taken, however, approximately on the line 3-3, Fig. 1, showing the means for controlling the supply of powder to the brush.

Referring now more in detail to the said drawings, which illustrate a practical embodiment of my invention and in which like reference characters refer to like parts throughout the several views, 1 indicates the brush-back, in which are suitably set 70 preferably elongated bristles 2 forming the brush of the article. Preferably integral with back 1, is an upturned corrugated or otherwise threaded annular flange 3. Fitting within the confines of flange 3 and covering the upper ends of the brush-bristles 2, is a disk 4, which forms substantially a part of the brush-back 1; and provided transversely in the brush-back 1 and its disk 4 at their approximate center, is a hole 80 or aperture, as at 5, for purposes shortly appearing.

6 indicates the main portion or body of the handle of the brush, which is preferably in the form of a tube or cylindrical shell of 85 suitable diameter relatively to the brush-back 1 and suitably corrugated or otherwise threaded at its lower end, as at 7, for detachable engagement with the flange 3. Forming substantially a part of shell 6 90 and fixed therein adjacent its lower end, is a bottom-providing disk 8 provided centrally with a plurality of perforations 9.

Fixed, as by diametrically opposite wings 10, to and upon the under face of disk 8 95 with its open upper end in alignment with the perforations 9, is a spout or funnel 11 depending at its lower end through the aperture 5 and down into the brush-bristles 2, as best seen in Fig. 1.

Intermediate the wings 10, the spout or funnel 11 is spaced from the under face of disk 8 and shaped to provide a slide-way, as at 12, for a gate 13 provided within its area with a plurality of perforations, as 105 at 14, and preferably provided at its opposite ends with angular downwardly disposed extensions 15-16, the perforations 14 being adapted for registration with perforations 9 of disk 8, but the gate 13 being normally held yieldingly with its perforations 14 out of registration with the per-

forations 9 by means of a preferably coiled spring 17 interposed between, and fixed at its ends to, the bent end 15 of the gate 13 and the adjacent wall of the shell 6. Fixed 5 at one end to the opposite bent end 16 of gate 13 and projecting for slidable movement through the wall of shell 6, as seen in Fig. 1, is a short rod or pin 18 for manipulating or actuating the gate 13 against the 10 tension of spring 17 for bringing the gate-perforations 14 into registration with the bottom perforations 9.

Shell 6 is also preferably corrugated or otherwise threaded at its upper end, as at 19, 15 and surmounting the shell 6 is a neck 20 likewise of suitable diameter relatively to shell 6 and suitably corrugated or otherwise threaded at its lower end, as at 21, for detachable engagement with the threaded up- 20 per end 19 of shell 6. Adjacent its lower end, neck 20 is provided with a perforated bottom or disk 22 substantially similar to shell bottom-disk 8; and fixed to and upon the under face of disk 22, is a strap 23 having perforations 24 alining or registering with the perforations of disk 22, the strap 23 being shaped, as best seen in Fig. 2, to provide a slideway for a yielding gate 25 constructed and operating substantially 25 similar in all respects to the lower gate 13. At its upper and preferably reduced end, neck 20 is provided with a perforated cap or outlet 26.

In use, shell 6 provides not only a handle 35 for conveniently manipulating the brush 2, but also, on detachment of neck 20, an easily filled container or magazine for talcum or other toilet-powder or the like. Shell 6 being so filled with the toilet-preparation, 40 and the gates 13 and 25 being normally yieldingly held as described in closed position with their perforations out of registration with the perforations of disks 8 and 22, it will be evident that the brush 2 may 45 be employed by the barber or other user as an ordinary brush. It will likewise be evident that the article, when inverted and the upper gate 25 actuated to open position to bring its perforations in registration with the registering perforations of strap 23 and disk 22, may be employed as an ordinary talcum-powder can, the powder contents 50 issuing or discharging from the magazine or shell 6 directly from the neck 20. However, 55 should the barber or other user wish to apply by means of the brush 2 the talcum-powder or other toilet preparation contained in shell 6, then finger-pressure upon the rod 18 serves to actuate the gate 13 to bring its 60 perforations 14 into registration with the

perforations 9 of disk 8, when the talcum powder contents of shell 6 will discharge through the spout or funnel 11 and into the applying brush 2.

By means of my new article, I obviate a separate handling of a talcum-powder receptacle and a brush, and am enabled to thus effect an economy both in time and labor. My new article is simple and compact in form and construction, may be inexpensively manufactured, and is highly efficient in performing its intended functions.

I am aware that changes in the form, construction, arrangement, and combination of the several parts of the combined toilet-powder receptacle and brush may be made and substituted for those herein shown and described without departing from the nature and principle of my invention.

Having thus described my invention, what 80 I claim and desire to secure by Letters Patent is:

1. A toilet-article including brush-bristles, in combination with a tubular handle for the bristles, the handle being adapted to contain a toilet-preparation and having at its opposite ends separate discharge-outlets for the preparation, one of which outlets leads into the brush-bristles, and means for independently controlling the discharge of the 90 toilet-preparation from the handle at said outlets.

2. A toilet-article including, in combination, brush-bristles, a tubular handle for the brush-bristles, the handle having a perforated bottom and being adapted to contain a toilet-preparation to be supplied to the brush-bristles, and means comprising a yielding gate having perforations adapted for registration with the perforations of 100 the bottom for controlling the supply of the toilet-preparation from the handle to the brush.

3. A toilet-article including, in combination, brush-bristles, a tubular handle for the 105 brush-bristles, the handle having a perforated bottom and being adapted to contain a toilet-preparation to be supplied to the brush-bristles, a funnel depending from the handle-bottom into the brush-bristles and 110 adapted for communication with the bottom perforations, and means comprising a yielding perforated gate having perforations adapted for registration with the perforations of the bottom for controlling the supply of the 115 toilet-preparation from the handle and through the funnel to the brush-bristles.

In testimony whereof I have signed my name to this specification.

GEORGE COSMOS.
